PORTABLE AIR CONDITIONER

Malcome Van Ike, Sun Valley, Calif.

Application May 16, 1955, Serial No. 36,013

Term of patent 3½ years

(Cl. D62—4)

Figure 1 is a top perspective view of a portable air conditioner embodying my new design.

Figure 2 is a plan view of the air conditioner.

Figure 3 is an end elevation of the air conditioner.

Figure 4 is an end elevation taken from the opposite end of the air conditioner than the view of Figure 3.

I claim:

The ornamental design for a portable air conditioner, substantially as shown.
